UNITED STATES PATENT OFFICE.

HERMAN O. ZBINDEN, OF SEATTLE, WASHINGTON, ASSIGNOR OF ONE-THIRD TO JOSEPH A. MARQUIS AND ONE-THIRD TO VICTOR E. GRAVES, BOTH OF SEATTLE, WASHINGTON.

CAN OPENER.

Application filed September 1, 1923. Serial No. 660,590.

To all whom it may concern:

Be it known that I, HERMAN O. ZBINDEN, a citizen of the United States, residing at Seattle, in the county of King and State of Washington, have invented new and useful Improvements in Can Openers, of which the following is a specification.

This invention relates to can openers, and aims to simplify the construction illustrated in patent numbered 1,446,804, to provide a device of this character which can be manufactured and sold at a nominal cost.

It is also the purpose of this invention to provide a can opener having a centering element adapted to penetrate the top of the can, and a cutting blade adapted to penetrate the side of the can adjacent the top, so that the latter can be removed in a quick and convenient manner, the blade being associated with the handle of the device to insure maximum strength and rigidity.

In carrying out the invention I make use of a cutting blade having two cutting edges, one of which is utilized to sever the top from a can by penetrating the side of the latter, while the other cutting edge can be used to penetrate the top of the can to remove the latter in the usual well known manner.

The nature and advantages of the invention will be better understood when the following detailed description is read in connection with the accompanying drawing, the invention residing in the construction, combination and arrangement of parts as claimed.

In the drawing forming part of this application, like numerals of reference indicate similar parts in the several views, and wherein:

Figure 1 is a plan view of the device showing it associated with a can for removing the top therefrom, with the cutting blade penetrating the side of the can.

Figure 2 is a bottom plan view of the device.

Figure 3 is an edge elevation.

Figure 4 is a sectional view taken on the line 4—4 of Figure 3, looking in the direction of the arrows.

Figure 5 is a sectional view taken on the line 5—5 of Figure 3, looking in the direction of the arrows.

The device forming the subject matter of the present invention embodies a handle

which is formed from a single length of suitable material, and of uniform width throughout. This material is bent upon itself to provide the members 10 and 11 respectively, which members are spaced apart for the major portion of their length. The member 10 terminates at one end to provide a U-shaped portion, the parallel sides of which are indicated at 12 and 13 respectively and the intermediate wall at 14. As clearly shown in Figure 3, the intermediate wall 14 is arranged in face to face contact with the other member 11, this wall 14 being of a length to arrange the parallel side 13 substantially flush with the adjacent end of the member 11. Arranged on the member 11 is a cutting blade 15, and this blade is secured in place by means of rivets or other suitable fastening elements 16 which are also utilized to secure the U-shaped portion of the member 10 to the member 11 of the handle. The U-shaped portion just referred to constitutes a guide for the centering element 17 which is arranged to slide through aligned openings 18 in the parallel sides of said portion, and also in the space between the handle members 10 and 11 respectively. The forward end of this centering element is offset as shown and terminates to provide a pointed extremity 19 adapted to penetrate the top of the can to be opened. The opposite end of the centering element is enlarged as at 20 to constitute a stop and thus limit the sliding movement of the element 17 in one direction preventing casual separation of the element from the handle.

As shown in Figures 1 and 2, the cutting blade 15 projects an appreciable distance beyond the forward end of the handle, and is sharpened to provide an inclined cutting edge 21 adapted to penetrate the side of the can, so that when the device is moved in a circle the entire top of the can is removed. This edge is bevelled so that the material of the can is turned inwardly during the cutting operation, thus eliminating projections and sharp points and edges which might otherwise injure the hands of the user. The blade 15 is also preferably formed with a hook like extension 22 having a cutting edge 23 which allows the device to be used in a manner similar to the old and well known type of can opener. In other words, this hook like

extremity is adapted to penetrate the top of the can adjacent the side thereof, and rocked upon a bearing or foot 24 until the entire top is removed. While the hook like extension 22 is herein shown as an integral part of the blade proper, I also contemplate making the hook like portion separate from the blade, so that the latter can be used independently of the hook like portion 10 when desired. Of course, the hook like portion when separable can be attached to the blade in any suitable manner. When the cutting edge 21 is used, the centering element is first used to make an opening in 15 the center of the top of the can, after which the handle is moved outwardly with the centering element in a horizontal position, until the blade 15 is moved beyond the edge of the can. The handle is then moved 20 toward the can until the cutting edge 21 penetrates the side thereof, whereupon the device can be moved in a circle to sever the top. It will be noted that the component parts of the device are very compactly arranged, thus affording the same a neat appearance and the desired strength and rigidity at those points where the device is subjected to stress and strain incident to its use. This is particularly true of the blade 15, 25 the body portion of which is of a length substantially equal to the length of the wall 30 the body portion of which parts together with the adjacent 14, which parts together with the adjacent

portion of the handle 11 are all riveted or otherwise secured together.

While it is believed that from the foregoing description, the nature and advantages of the invention will be readily apparent, I desire to have it understood that I do not limit myself to what is herein shown and described and that such changes may be 40 resorted to when desired as fall within the scope of what is claimed.

Having thus described the invention, I claim:

A can opener embodying a handle formed from a single length of material and including parallel members spaced apart for the major portion of their length, one of said members including a U-shaped end portion, the parallel sides of which are 50 provided with aligned openings, a centering element slidable through said openings and in the space between the handle members, said element terminating to provide an offset pointed extremity, a cutting blade 55 arranged on the other member of the handle and including an inclined cutting edge projecting forwardly of the handle, and a cutting edge projecting from one side thereof, and means for securing the cutting 60 blade and the adjacent ends of the handle members together.

In testimony whereof I affix my signature.

HERMAN O. ZBINDEN.
